W. A. SHELTON,
AUXILIARY HEAD FOR HEATERS,
APPLICATION FILED FEB. 13, 1919.

1,311,252.

Patented July 29, 1919.

Inventor:

William A. Shelton,
by Oscar Middleton Donaldson, Jr.,
Atty's.

UNITED STATES PATENT OFFICE.

WILLIAM A. SHELTON, OF AKRON, OHIO, ASSIGNEE TO THE WILLIAMS FOUNDRY & MACHINE COMPANY, OF AKRON, OHIO, A CORPORATION OF OHIO.

AUXILIARY HEAD FOR HEATERS.

1,311,252.

Specification of Letters Patent. Patented July 29, 1919.

Application filed February 13, 1919. Serial No. 276,826.

To all whom it may concern:

Be it known that I, WILLIAM A. SHELTON, a citizen of the United States, and resident of Akron, Ohio, have invented certain new and useful Improvements in Auxiliary Heads for Heaters, of which the following is a specification.

My present invention relates to improvements in doors for vulcanizers or heaters, such as are used for vulcanizing rubber goods.

The invention aims to provide means by which the operator is enabled to observe the condition of the contents of the vulcanizer after the head or door has been applied, and can thus adjust any irregularities before the final sealing of the heater.

The invention includes the novel features of construction and arrangement and combination of parts hereinafter described and particularly defined by the appended claims.

An embodiment of my invention is illustrated in the accompanying drawing in which,

Figure 1 is a plan view of the vulcanizer head, and,

Fig. 2 is a transverse sectional view.

Referring by reference characters to this drawing at A is indicated a sufficient portion of a vulcanizer or heater and B designates the head or door thereof, which may be detachably secured to the body of the heater in the usual or any desired manner. The character of articles vulcanized in these heaters requires the heads or doors to be of substantially full diameter of the heater and such doors or heads are therefore of great size and weight and as the contents must be sealed steam tight considerable careful work

is involved in applying the heads or doors. To enable the contents of the heater to be inspected after the head has been applied I provide an auxiliary head 1 which covers an opening in the vulcanizer head, preferably arranged centrally thereof. I prefer to form the auxiliary head circular and of convex form, and secure it to the main head by providing it with peripheral lugs 3 designed to take under corresponding lugs 4 on an annular flange 5 carried by the main head B.

The auxiliary head may be provided with a groove or grooves for the reception of packing material to effect a tight joint.

The auxiliary head is provided with a central opening 2 for the passage of piping by which fluid may be admitted to the tires or other articles in the vulcanizer, this opening being in alignment with an open passage 6 in the main head B.

What I claim is:

1. The combination with the removable head of a vulcanizer having an observation opening, of a removable auxiliary disk-shaped head closing said opening.

2. A removable vulcanizer head having a central opening and an annular flange therearound provided with inwardly projecting lugs, and an auxiliary head having coacting lugs.

3. A convex vulcanizer head having an opening and a convex auxiliary disk-shaped head having its edge removably clamped against said vulcanizer head.

In testimony whereof, I affix my signature.

WILLIAM A. SHELTON.
